US00D933838S

(12) **United States Design Patent** (10) **Patent No.:** **US D933,838 S**
Hwang (45) **Date of Patent:** **** Oct. 19, 2021**

(54) **ELECTROCARDIOGRAPHIC DEVICE**

(71) Applicant: **HEXACHECK INC.**, Daejeon (KR)

(72) Inventor: **In-Duk Hwang**, Sejong (KR)

(73) Assignee: **HEXACHECK INC.**, Daejeon (KR)

(**) Term: **15 Years**

(21) Appl. No.: **35/509,759**

(22) Filed: **Jan. 7, 2020**

(80) **Hague Agreement Data**

Int. Filing Date: **Jan. 7, 2020**

Int. Reg. No.: **DM/206259**

Int. Reg. Date: **Jan. 7, 2020**

Int. Reg. Pub. Date: **Jul. 10, 2020**

(30) **Foreign Application Priority Data**

Jul. 12, 2019 (KR) 30-2019-0033615

(51) **LOC (13) Cl.** **24-01**

(52) **U.S. Cl.**

USPC **D24/187**

(58) **Field of Classification Search**

USPC D24/206, 168, 187, 200

CPC .. A61B 5/02438; A61B 5/6823; A61B 5/0006

See application file for complete search history.

(57) **CLAIM**

The ornamental design for an electrocardiographic device, as shown and described.

DESCRIPTION

1. Electrocardiographic device

1.1 : Bottom Front Perspective

1.2 : Front

1.3 : Back

1.4 : Left

1.5 : Right

1.6 : Top

1.7 : Bottom

1.8 : Top Back Perspective

The dashed broken lines in the figures show portions of the electrocardiographic device that form no part of the claimed design.

1 Claim, 8 Drawing Sheets
